DESIGN FOR A COMBINATION DESK UNIT

Chester B. Gooding, Wakefield, Mass.

Application May 5, 1939, Serial No. 84,816

Term of patent 7 years

To all whom it may concern:

Be it known that I, Chester B. Gooding, a citizen of the United States, residing at 15 Central Street, Wakefield, in the county of Middlesex, and State of Massachusetts, have invented a new, original, and ornamental Design for a Combination Desk Unit, of which the following is a specification, reference being had to the accompanying drawing, forming a part thereof.

Figs. 1 and 2 are a plan view and a side elevation, respectively, of a combination desk unit, showing my new design.

I claim:

The ornamental design for a combination desk unit, substantially as shown.

CHESTER B. GOODING.
